Specification for Design.

Patented July 15, 1919.

Application filed June 18, 1915. Serial No. 34,944. Term of patent 14 years.

To all whom it may concern:

Be it known that I, HENRY J. WOODWARD, citizen of the United States, residing at Peoria, in the county of Peoria and State of Illinois, have invented a new, original, and ornamental Design for a Powder-Box, of which the following is a specification, reference being had to the accompanying drawing, forming part thereof.

Figure 1 is a plan view of the box.

Fig. 2 is a side elevation of the box showing its longest measurement; and,

Fig. 3 is an end elevation showing the box in its narrowest measurement.

I claim:—

The ornamental design of a powder box as shown.

In testimony whereof I affix my signature, in presence of two witnesses.

HENRY J. WOODWARD.
